UNITED STATES PATENT OFFICE.

BENJAMIN J. LOWMAN, OF BRIDGEPORT, ALABAMA, ASSIGNOR TO HIMSELF
AND EDWARD L. C. WARD, OF SAME PLACE.

FIRE AND BURGLAR ALARM.

SPECIFICATION forming part of Letters Patent No. 570,258, dated October 27, 1896.

Application filed December 27, 1894. Serial No. 533,089. (No model.)

To all whom it may concern:

Be it known that I, BENJAMIN J. LOWMAN, of Bridgeport, in the county of Jackson and State of Alabama, have invented a new and Improved Fire and Burglar Alarm, of which the following is a full, clear, and exact description.

My invention relates to improvements in fire and burglar alarms; and the object of my invention is to produce a very simple apparatus which may be applied to any ordinary push-button connected with the usual annunciators, and which is arranged so that it does not interfere with the regular working of the push-button, but has automatic means for pushing the button and sounding the alarm in case its tension-wire is slackened either by a fire or the breaking of a building.

A further object of my invention is to produce a simple means of connecting the wire to the push-button attachment so as to hold the attachment normally out of contact with the push-button, but to arrange this wire so that if it is severed by fire or is slackened in any way the push-button will be automatically struck and the annunciator sounded.

To these ends my invention consists of certain features of construction and combinations of parts, which will be hereinafter described and claimed.

Reference is to be had to the accompanying drawings, forming a part of this specification, in which similar figures and letters of reference indicate corresponding parts in all the views.

Figure 1 is a sectional view showing the application of my improved apparatus to the rooms of a building and to a push-button, the view also showing the circuit which is to be closed by the push-button. Fig. 2 is an enlarged detail longitudinal section on the line 2 2 of Fig. 3 of my improved apparatus, showing the striking-pin out of contact with the push-button. Fig. 3 is a section on the line 3 3 of Fig. 2. Fig. 4 is a section similar to Fig. 2, but with the striking-pin and supplemental push-button pushed inward to sound an alarm. Fig. 5 is a sectional plan showing the application of my apparatus to a door to serve as a burglar-alarm. Fig. 6 is a detail sectional view showing the application

of my invention to a push-button substantially like the ordinary one and with the circuit open. Fig. 7 is a similar view to Fig. 6, but showing the circuit closed by the breaking of the fusible wire; and Fig. 8 is a sectional front elevation or plan of the push-button.

The apparatus is used in connection with a push-button 10, which may be of any usual construction and will not therefore be described in detail, this button being held in a block 9, although it may be fastened in any convenient way, and it has the customary button 11, which on being pressed closes a circuit through the wires *a* and *a'*, which circuit includes an alarm 12 and battery A. The circuit may also be made to include one or any number of automatic push-buttons.

Opposite the button 11 is a depressible striking-pin 13, which has at its inner end a head 14 to engage the button 11, and the outer end of the pin 13 is provided with a second or supplemental button 15, which may be pressed when the push-button is to serve its normal purpose, and which on being pressed causes the pin 13 to press inward on the button 11. The pin 13 is also provided with a collar 16, which is adapted to be struck and moved inward by a spring 17, having sufficient tension to cause the button 11 to be pressed hard enough to close the circuit through the wires *a* and *a'* when the said spring 17 is released. This spring may be fastened in any convenient manner, but it is preferably secured to a longitudinally-slotted plate 18, which is fastened to the block 9 so as to serve in a measure as an escutcheon-plate and encircle the outer part of the push-button 10 and the striking-pin 13.

The spring 17 is held at its free end out of contact with the collar 16 by a wire 21, which extends outward over a guide-pulley 20, journaled in the lugs 19 on the plate 18, or over any other suitable guide, and the wire extends out through a hole 22 in one end of the casing 25, which covers the greater part of the apparatus, the wire passing thence to suitable guides 23, arranged in desired places around the walls of a room or rooms, and the wire has at necessary intervals fusible parts 24, which melt in case the temperature gets

dangerously high, and therefore the melting of one of these parts releases the tension of the wire and permits the spring 17 to swing inward and press upon the collar 16, thus 5 forcing the striking-pin 13 against the button 11 and closing the electric circuit and sounding an alarm. The striking-pin 13 moves freely through the spring 17, and it will be seen that by pressing on the button 15 the 10 button 11 will be pressed in the usual way.

The casing 25, which incloses the apparatus, is adapted to be fastened to the block 9 or other support to which the apparatus is attached, and the casing has an opening 26 opposite the button 15, so that the thumb may 15 be easily pressed upon the button when the push-button 10 is to be operated.

In Fig. 5 I have shown one means of utilizing the apparatus for a burglar-alarm, and 20 as here illustrated a wire 27 connects with the button 15 and extends over a toggle-lever 28, which is pivoted to a second lever 29, this being pivoted in a support 30, and the outer end of the wire 27 is made fast to the wall of 25 a room or to a similar support and the tension of the wire causes the toggle-levers to be held normally straight with their stops 31 abutting and preventing the levers from doubling up. A wire 32, which extends through 30 suitable guides 33, is connected with the lever 28 near the joint and is also attached to the door 34, and when the door is opened the wire 32 is pulled, thus doubling up the levers 28 and 29, as shown by dotted lines in 35 Fig. 5, and relieving the tension of the wire 27, which permits the spring 17 to act as already described and close the push-button and annunciator-circuit. The circuit may 40 also be arranged to ring any automatic bell. I have shown this particular arrangement for utilizing the device as a burglar-alarm simply to illustrate the practicability of so using it, but it will be understood that very many 45 different devices may be used to release the spring 17 without in the least affecting the principle of the invention.

In Figs. 6 to 8 I have shown my improved appliance in connection with a push-button which is substantially like the usual push-button, but which is changed a little to meet 50 the requirements of the alarm. The push-button is provided with a spring 36, connecting with the wire *a* of the circuit and terminating at one end in a contact-piece 37, and the 55 push-button has also a spring-metal contact-piece 38, and the upper or outer end of this contact-piece is bent, as shown at 39, so as to contact with the contact-piece 37.

The bent end 39 of the contact-piece 38 is 60 held out of contact with the contact-piece 37 by the fusible wire 21^a, which is passed in from the back of the push-button, as shown in Fig. 6, and thus the push-button may be used in the ordinary way by pushing in the

button 11, which is attached to the contact-piece 37, the arm 36 of which is also of spring metal. When the button is pressed, the contact-piece 37 engages or touches the bent end 39 of the contact-piece 38, thus closing the circuit. When the wire 21^a is broken by heat 65 or in any other way, it releases its tension on the end 39 of the contact-piece 38 and the said bent end springs outward into contact with the contact-piece 37, thus closing the circuit and sounding an alarm. 70

It will be seen where ground-circuit is used the reverse action of spring may be made upon the same principles of the invention. 75

Having thus described my invention, I claim as new and desire to secure by Letters Patent—

1. The combination of a push-button, a supplemental or second push-button adapted to engage with the first-named button, said supplemental button being adapted to be moved 85 independently of the other button, and a spring arranged to hold the two buttons out of engagement with one another and adapted to permit the operation of the supplemental button, substantially as set forth. 90

2. The combination of a push-button, a supplemental or second push-button adapted to engage the first-named button, said supplemental button being adapted to be moved independently of the other button, and a spring 95 arranged to hold the two buttons out of engagement with one another and adapted to permit the operation of the supplemental button, substantially as set forth.

3. The combination, with the push-button, 100 of a second button adapted to engage the push-button, a spring encircling the shank or pin of the second button and adapted to press it against the push-button, and a fusible wire extending from the free end of the spring to 105 suitable supports, substantially as described.

4. The combination, with the push-button, 110 of a striking-pin forming a second button to engage the push-button, the pin having a collar thereon, a spring having its free end adapted to engage the collar, and a fusible wire connected with the free end of the spring and extending outward over a suitable guide, substantially as described. 115

5. The combination, with the push-button, 115 of a second button having an inwardly-extending pin or shank to engage the push-button, a spring fastened at one end to a support and having its free end encircling the pin, a fusible wire connected with the spring to hold 120 it out of engagement with a collar on the pin, and a casing covering the apparatus and provided with a hole for the second button, substantially as described.
